UNITED STATES PATENT OFFICE

WILLIAM H. WALKER, OF MARTINEZ, GEORGIA, ASSIGNOR OF ONE-HALF TO
PATRICK J. SULLIVAN, OF AUGUSTA, GEORGIA, AND EDWARD EVERETT,
OF WILMINGTON, NORTH CAROLINA.

AIR-BRAKE.

SPECIFICATION forming part of Letters Patent No. 438,038, dated October 7, 1890.

Application filed February 14, 1890. Serial No. 340,489. (No model.)

To all whom it may concern:

Be it known that I, WILLIAM H. WALKER, of Martinez, in the county of Richmond and State of Georgia, have invented a new and useful Improvement in Air-Brakes, of which the following is a specification.

My invention is an improvement relating especially to that class of steam and air brakes in which a reduction of pressure in the so-called "brake-pipe" results in the application of the brake; and the invention seeks to provide a simple means by which to automatically effect the desired reduction of pressure in certain instances—as, for example, if the track should spread, the truck mount the rail, an axle break, or a rail break; and the invention consists in certain features of construction and novel combinations of parts, as will be hereinafter described and claimed.

In the drawings, Figure 1 is a top plan view of a truck provided with my improvements. Fig. 2 is a cross-sectional view showing my improvements in connection with a part of a car. Fig. 3 is a bottom plan view of the guards, provided with the improvements. Figs. 4 and 5 are detail views showing a somewhat different construction, and Fig. 6 is a sectional view on about line 6 6 of Fig. 1.

Inasmuch as the brake-shoes and the devices for supporting and operating the same may be of any suitable or well-known kind, I have not thought it necessary to illustrate or describe the same.

The so-called "brake-pipe" A may be supported on or below the framing of the car in the manner shown or in any other suitable manner. I provide this pipe A with a valve or valves B, which may be of the turn-cock variety shown, or may be constructed after the fashion of the conductor's valve used in air-brakes, or may be of any other suitable construction to be opened to reduce the pressure in the pipe or closed to maintain such pressure. A bar or connection C is arranged to operate this valve, and has a foot-like part or portion D, arranged in case of accident to engage the rail or some other part of the track and be operated thereby to open the valve B, and so reduce the pressure in the brake-pipe and cause the brake to be applied.

In proceeding to describe the particular manner shown of carrying out my invention it may be stated that it is manifest that there may be various changes of the details of construction without departing from some of the broad principles of the invention.

The valve B is shown as a turn-valve having a crank-arm E, provided with a wrist or pin e. This pin e enters the slot f of a crank-arm F, which extends from a journaled shaft G, such shaft G being also provided with a crank-arm H, to which is connected the operating-bar or connection C, which extends thence downward and has a part or portion D arranged to be engaged by the rail or other part of the track when the truck is abnormally lowered in case of accident, as will be further referred to hereinafter.

The truck is shown as provided with a guard having two shoes J at the opposite sides, one of such shoes at each side being provided in its under side with a groove or seat K, for the foot portion D, which partially fits in such groove or seat, as shown, openings k k' leading up from respectively the inner and outer ends of the seat K through the shoe. The connecting-bar C extends down through opening k, has its foot D fitted in seat K, and has a small upward extension d, which projects up through opening k', and is threaded to receive the nut d', which may be set to vary the distance to which the bar C may descend and consequently limit the extent of the movement of such bar.

In operation upward movement of bar C will by crank H turn the shaft G to cause the arm or crank F to rock and so turn and open the valve B by means of the arm E, as will be understood from Fig. 6. The purpose of the guard-shoes is in case of accident—such as the breakage of a wheel or axle or spreading of the track—the shoes will fall upon and slide along the rails and operate to permit a certain movement of the car and also serve to brake the same and cause it to stop.

It will be understood that the safety-guard will hold the car on the track in any contingency, and that at the same time through the mechanism described the brakes will be instantly thrown on, thereby stopping the car.

- as quickly as if thrown on by the conductor or engineer. Manifestly any suitable valve may be used instead of that shown, and such valve may be used in any suitable connection, so its opening will effect the desired reduction of pressure in the brake-pipe. It will also be seen that the diagonally-opposite guard-shoes support the foot portions or trips of the operating-bar, so that whether the car is moving in one or the other direction one of the front shoes has a connection extended from it to a valve in the brake-pipe, and as such valves and connections are both alike the description of one will answer for both.
- 15 The pin *e* of arm *E*, which enters slot *f* of arm *F*, fits loosely in such slot and is of sufficient length to permit it to remain properly in such slot when the truck is rounding a curve.
- 20 It may be preferred in some instances to use different forms of valve at the opposite sides of the truck, as shown in Figs. 4 and 5, a turn-plug valve being used at one side and a lift-valve at the other side.
- 25 Having thus described my invention, what I claim as new is—
1. The combination, with the truck and the guard-shoe, of a brake-operating attachment having a trip foot or portion supported below said shoe and arranged to be actuated by the rail where the shoe drops thereon, substantially as set forth.
  2. The combination of the car-truck provided with a guard having shoes, of the brake-pipe having a valve and a bar or connection arranged to operate such valve and having a foot-like part or portion projecting below the guard-shoe and arranged to be elevated by the rail when the shoe drops onto such rail, substantially as set forth.
  3. The combination of the truck, the guard having a shoe provided in its under side with a groove or seat, the brake-pipe having a valve, and the bar or connection for operating such valve, said bar or connection having a foot-like portion fitting partially within the groove or seat in the guard-shoe, all substantially as set forth.
  4. The combination, with the truck and its guard having a shoe, of an air-brake attach-

ment having a trip foot or portion supported below said shoe and arranged to be actuated by the rail when the shoe drops thereon, substantially as set forth.

5. The combination of the truck, the guard having a shoe, the brake-pipe having the valve, the bar or connection arranged to operate the said valve and provided with a threaded portion and with a foot portion arranged to extend below the guard-shoe, and an adjusting-nut on the threaded portion, substantially as set forth.

6. The combination of the truck having a guard-shoe provided in its under side with a groove or seat, the brake-pipe and its valve, the rod or connection arranged to operate such valve and having a foot portion to fit in the groove or seat of the guard-shoe and a threaded portion extended above such shoe, and a nut on the said threaded portion, all substantially as and for the purposes set forth.

7. The combination of the truck, the guard-shoe provided in its under side with a groove or seat, and the brake-operating attachment having a foot-like portion fitting partially within the groove or seat in the guard-shoe, all substantially as described, and for the purposes set forth.

8. The combination, substantially as hereinbefore described, of the truck having the guard formed with a shoe and having in the under side thereof a groove or seat, the brake-pipe having a valve, the shaft having two crank-arms, one of which is connected with the valve, and the bar or connection connected with the other crank-arm and having a foot-like portion fitting partially within the groove or seat of the guard-shoe, all substantially as and for the purposes set forth.

9. In an apparatus substantially as described, a guard having two shoes over each rail and having the diagonally-opposite shoes provided with trips or foot-like portions connected with and arranged to actuate the air-brake mechanism, substantially as set forth.

WILLIAM H. WALKER.
